UNITED STATES PATENT OFFICE.

ALWIN E. ANDREE, OF LAKE LINDEN, MICHIGAN.

STENCIL-HOLDER.

No. 806,617.

Specification of Letters Patent.

Patented Dec. 5, 1905.

Application filed July 22, 1905. Serial No. 270,821.

To all whom it may concern:

Be it known that I, ALWIN E. ANDREE, a citizen of the United States of America, residing at Lake Linden, in the county of Houghton and State of Michigan, have invented new and useful Improvements in Stencil-Holders, of which the following is a specification.

This invention relates to means for securing decorative stencils to walls or ceilings.

A decorator or painter when putting a stencil on the wall, and especially on the ceiling, must either employ a helper or personally tack his stencil in place. The former method is expensive and the latter inconvenient, because of the difficulty in holding the stencil and tack and driving the tack at the same time. Furthermore, the ordinary method of tacking is objectionable, as the wall or ceiling is frequently soiled by the fingers holding the tack and the tacks are constantly displaced from the fingers in driving and removing them and drop upon the floor.

The object of the present invention is to provide simple and effective means for holding, the tacks or fastenings upon the stencil, so that they can be conveniently driven into the wall or ceiling to secure the stencil thereto and as conveniently withdrawn to detach the stencil without becoming unfastened from the latter.

The preferred embodiment of the invention is illustrated in the accompanying drawings, in which—

Figure 1 is a longitudinal section through the device applied to a stencil. Fig. 2 is a plan view of the device detached, and Fig. 3 is a cross-sectional view taken on line 3-3 of Fig. 1. Fig. 4 is a view similar to Fig. 1, showing a modified construction of holding device. Fig. 5 is a plan view of the form of holding device shown in Fig. 4. Fig. 6 is a cross-section taken on line 6-6 of Fig. 5.

In carrying my invention into practice I provide a holding device 1, comprising a comparatively long and narrow strip of sheet metal bent or folded upon itself to form a body portion 2 and a clamping portion 3, the main body and clamping portion being integrally connected at one end and spaced to form a clasp to receive and engage the edge of the stencil 4. The body portion 2 is bent or offset at its free end to form a holding-arm 5, which lies on a plane beyond the same and parallel therewith and with the clamping portion 3. The arm 5 is provided with an

opening 6 for the passage of the shank of the tack or fastening 7, which is adapted to extend through the stencil 4 for insertion into the wall or ceiling to hold the contiguous portion of the stencil in place. The free end of the arm 5 is longitudinally slotted to form a tongue 8, which is integrally connected at its inner end to said arm immediately in rear of the opening 6 and is adapted to engage and lie in the path of the head of the tack 7 to hold the same from outward movement and disconnection, so that the tack when once applied will constitute a permanent fixture and may be repeatedly used for securing the stencil in place. In the operation of applying the tack the tongue 8 is bent back to permit the tack to be inserted in the opening 6, after which the tongue is bent down on the arm again to hold the tack in applied position. The tack is thus applied and forced through the stencil for use after the holding device has been slipped onto an edge of the stencil, as will be readily understood.

The stencil is provided with one or more of the holders, and in applying the same to a wall or ceiling it will be seen that it is simply necessary to hold the stencil in place and to strike the tongue 8 over the head of the tack with a hammer, whereupon the tack will be driven into the wall or ceiling to secure the stencil thereto. As the tack is held upon the stencil, the necessity of the operator holding the same is obviated, thus enabling the stencil to be applied more conveniently and without liability of the fingers of the operator coming in contact with and soiling the wall or ceiling. To detach the tack, it is simply necessary to insert the blade or point of an instrument beneath the clamping portion 3 and force the same outward from the wall or ceiling. In this operation also the tack will be held by the holder 1 and prevented from dropping on the floor.

In the modified embodiment of the invention shown in Figs. 4, 5, and 6 the body portion 9 of the holding device is provided with an offset holding-arm 10 and is longitudinally slotted to form oppositely-disposed spring clamping-arms 11 to hold the stencil against said body portion, the latter thus forming a clasp to secure the arm 10 to the stencil, and the arm 10 is provided with integral spring-fingers 12, projecting inwardly on the under side thereof from its free end, said fingers being spaced to form a throat or passage for the reception of the fastening 7, the

head of which is adapted to lie between said spring-fingers and the body of the arm 10. The mode of use of this form of the invention will be readily understood from the drawings.

From the foregoing description, taken in connection with the accompanying drawings, the construction and mode of operation of the device will be readily understood by those versed in the art and its manifold advantages appreciated.

Having thus described my invention, what I claim is—

- 15 1. A fastening for stencils comprising a strip of sheet metal bent to form a body portion having a holding-arm formed with an opening, a fastening inserted in said opening, and a spring-tongue upon the arm to hold the fastening.
- 20 2. A fastening for stencils comprising a spring-clasp having an opening to receive a fastening member and a spring-tongue to hold said member in applied position.
- 25 3. A stencil-holder comprising a resilient strip of metal bent to form a clasp to engage the edge of the stencil, and a holding-arm projecting beyond the clasp, said holding-arm being provided with means for retaining a tack or similar fastening.
- 30 4. A stencil-holder comprising a resilient metallic strip folded at one end upon itself to form a spring-clasp to engage the edge of the stencil and having its opposite end extended to form an arm, said arm being provided with

means for attaching a fastening element 35 thereto.

5. A stencil-holder comprising a strip of spring metal bent to fold at one end upon itself to form a spring-clasp to engage the edge of a stencil and having its opposite end extended and offset to form an arm provided with means for detachably connecting a tack or similar fastening thereto.

6. A stencil-holder comprising a resilient metallic strip folded at one end to form a 45 clasp and having its opposite end extended to form an arm, said arm being provided with a spring member to retain a tack or similar fastening in engagement therewith.

7. A stencil-holder comprising a resilient 50 strip of metal bent at one end to form a clasp to engage the edge of a stencil and having its opposite end projecting beyond the clasp to form an arm offset from the plane of the clasp, said arm having a portion bent to form 55 a tack-retaining tongue.

8. A stencil-holder comprising a resilient strip of metal bent at one end to form a clasp and having its opposite end extended in an offset to form an arm, said arm having a tack- 60 receiving opening therein, and a spring-clasp to retain the tack therein.

In testimony whereof I affix my signature in presence of two witnesses.

ALWIN E. ANDREE.
